United States Patent Office

Des. 211,691
Patented July 16, 1968

211,691

CABINET FOR DATA PROCESSING EQUIPMENT

James Jordan, West Acton, Mass., assignor to Digital
Equipment Corporation, Maynard, Mass.

Filed Nov. 23, 1966, Ser. No. 4,778

Term of patent 14 years

(Cl. D26—5)

FIG. 1

FIG. 2

FIG. 4

FIG. 3

FIG. 5

FIG. 1 is a front perspective view of cabinet for data processing equipment embodying my new design;

FIG. 2 is a rear view thereof;

FIG. 3 is a top view thereof;

FIG. 4 is a side view thereof, and

FIG. 5 is a bottom view thereof.

The dominant features of my design reside in the portions shown in full lines.

I claim:

The ornamental design for a cabinet for data processing equipment, substantially as shown and described.
